Primary Examiner — Zenia I Bennett(74) *Attorney, Agent, or Firm* — Boyle Fredrickson. S.C.(57) **CLAIM**

The ornamental design for a hand dryer, substantially as shown and described.

DESCRIPTION

FIG. 1 is a front, raised perspective view of a hand dryer according to the invention;

FIG. 2 is a front view of the hand dryer of FIG. 1;

FIG. 3 is a rear view of the hand dryer of FIG. 1;

FIG. 4 is a right side view of the hand dryer of FIG. 1;

FIG. 5 is a left side view of the hand dryer of FIG. 1;

FIG. 6 is a top view of the hand dryer of FIG. 1;

FIG. 7 is a bottom view of the hand dryer of FIG. 1; and,

FIG. 8 is a front, lowered perspective view of the hand dryer of FIG. 1.

The broken lines shown in the drawings form no part of the claimed design. All surfaces not shown form no part of the claimed design. Further, the hand dryer is shown with a symbolic break in its width. The appearance of any portion of the hand dryer between the break lines forms no part of the claimed design.

1 Claim, 8 Drawing Sheets(56)
